INVENTOR

Wm H. Elliot

UNITED STATES PATENT OFFICE.

WILLIAM H. ELLIOT, OF BROOKLYN, NEW YORK.

FIRE-ARM.

SPECIFICATION forming part of Letters Patent No. 325,513, dated September 1, 1885.

Application filed July 11, 1885. (No model.)

To all whom it may concern:

Be it known that I, WILLIAM H. ELLIOT, a citizen of the United States, residing at Brooklyn, in the county of Kings and State of New York, have invented a new and useful Improvement in Fire-Arms, of which the following is a specification.

The object of my invention is to provide a more practical and a more reliable method of 10 retracting the firing-pin of breech-loading or magazine fire-arms than any now in use; and the nature of my invention consists in the novel assemblage of certain co-operative devices which shall accomplish the above objects by 15 the mechanism illustrated in the accompanying drawings, in which—

Figure 1 is a vertical longitudinal section of the arm, showing some of the limb-work in elevation. Fig. 2 is a vertical longitudinal 20 section of a bolt and firing-pin and an elevation of the retracting-lever with a portion of the hammer.

My invention is applicable to any kind of arm having a bolt or breech-block for closing 25 the chamber which moves in a line with the barrel and a hammer which is brought to full-cock by said bolt in its backward movement. It is, however, more particularly applicable to the arms shown in my patents of September 30 14, 1880, and September 18, 1883, to which patents, for the better understanding of this application, I desire to make special reference.

The hammer *m* is pivoted in the receiver at *m'*, under or nearly under the rear end of the 35 bolt when the arm is closed, and is brought to full-cock by the bolt in its rearward movement for opening the arm, as shown in Fig. 1. The retracting-lever *i* is pivoted in the bolt at *i'*, and when the arm is closed and the hammer 40 down occupies the position in relation to the bolt shown in Fig. 2. The hammer is provided with the curved projection *n*, which serves the purpose of closing the rear end of the receiver when the hammer stands at full-

cock. The projection *n* forms the recess *n'*, for the reception of the rear end of the brace *r* when the arm is fully open, said brace being pivoted to the forward end of the bolt and provided with locking-shoulders *r''* within the 45 receiver, and cut away centrally on the upper and lower side of its rear end, as shown by

open lines, to enable it to enter the recess *n'* without clashing.

The connecting-strap *S* is pivoted at *S'* to the arm of the brace, and is operated by handle *S''*, shown in open lines, as represented in the last one of the before-mentioned patents.

The firing-pin *e* is mortised through for the reception of the retracting-lever.

As the bolt moves backward in opening the 60 arm the free end of the retracting-lever *o* is drawn up or over the projection *n* from the position shown in Fig. 2 to that shown in Fig. 1, which causes the arm *o'* of the retracting-lever to force the firing-pin back, or, in other 65 words, to retract it.

The relative position of the retracting-lever, bolt, and hammer is a matter of importance. The retracting-lever should be so located in the bolt that only when the firing-pin is fully 70 retracted the bolt will be far enough back to allow a fresh cartridge to be inserted in the chamber, either by hand or from the magazine. This feature makes it impossible to place a fresh primer before the firing-pin without first 75 retracting said pin. Open lines at *b'*, Fig. 1, show that a cartridge cannot be inserted in the chamber until after the firing-pin has been retracted.

These devices should be so arranged in relation to each other that after the hammer has been brought to full-cock by the backward movement of the bolt the retraction of the firing-pin will commence. By this arrangement of parts the cocking of the hammer and 80 the retraction of a rusted firing-pin could not both at the same time oppose the movement of the breech mechanism.

The hammer constructed, as described, with the projection *n* and recess *n'* serves the triple 90 purpose of closing the rear end of the receiver when the arm is cocked, of furnishing room for the brace when the arm is open, and of actuating the retracting-lever during the rearward movement of the bolt.

Having described my invention, what I desire to have secured to me by Letters Patent of the United States is—

1. In a fire-arm, the combination of the longitudinally-reciprocating bolt *e*, the firing-pin 100 *e*, extending longitudinally through said bolt, the lever *i*, hung in said bolt, and the ham-

mer m , pivoted within the receiver, said lever having one arm, o , actuated by the projection n of the hammer, and the other arm, o' , in connection with said pin, the arrangement of 5 said parts in relation to each other being such that only when the firing-pin is fully retracted will the bolt be far enough back to allow a fresh cartridge to be inserted in the chamber of the arm, substantially as and for the purpose specified.

2. In a fire-arm, the combination of the longitudinally-reciprocating bolt c , the firing-pin e , extending longitudinally through said bolt, the lever i , hung in said bolt, and the hammer m , pivoted within the receiver, said lever 10

having one arm, o , actuated by the projection n of the hammer, and the other arm, o' , in connection with said pin, the arrangement of 20 said parts in relation to each other being such that only when the firing-pin is fully retracted will the bolt be far enough back to allow a fresh cartridge to be inserted in the chamber of the arm, and that the retraction of the firing-pin will begin after the hammer has been brought to full-cock by the bolt, substantially 25 as and for the purpose specified.

WM. H. ELLIOT.
